CHARACTER READING SYSTEM

Tirey C. Abbott, Jr., Los Angeles, and Herbert L. Bernstein, Inglewood, Calif., assignors to The National Cash Register Company, Dayton, Ohio, a corporation of Maryland

Filed Dec. 23, 1959, Ser. No. 861,469
20 Claims. (Cl. 340—146.3)

The present invention relates to systems for reading printed characters, and more particularly to such a system which provides for scanning a printed character a plurality of times to determine the locations of predefined portions thereof, and then scanning these portions of the character to sense the relative position of segments of lines printed therein to form the character.

One of the most direct and practical over-all approaches to providing character recognition systems appears to be to adapt as much of the existing equipment in business practice as is possible to perform the required functions. Thus, although magnetic detecting systems have at times been suggested in the past, the optical detection system is actually a much simpler and more compatible approach since conventional inking and printing equipment can be employed, with the style of type used to form the characters being in most instances the major change requirement. Moreover, in business systems where documents are not handled generally by the public, the main advantage attributed to magnetic systems, which is that reliable reading of the printing is not affected by over-stamping, is of minor importance because of the internal control that can be made in many business establishments in this respect.

In view of the above, it appears that the approach of reading characters as inked and printed by conventional equipment is highly desirable and worth pursuing, but to accomplish this, other factors must be considered and overcome such as the necessity of providing optical reading apparatus which is adapted to read character print provided by the relatively inexpensive conventional printing equipment, which print normally needs only to be sufficiently exact in registration and form so as to be recognized and distinguished by the human eye. Furthermore, the paper conventionally used for printed information in the day-by-day business practice may have defects therein, such as foreign matter, which although of no consequence and virtually unnoticeable to the human eye, may be intolerable when reliable reading by automatic equipment is desired.

Thus, in the printing of characters, by conventional wheel-type printing equipment for example, such as employed in cash register and other widely used devices of a similar nature, misregistration or variation in the spatial relation of one character with respect to other characters in a row, or relative to a normal position in a row, is likely to occur; or the character may be slightly skewed or tilted from its normal position. In such equipment, the misregistration or difference in displacement between the highest and lowest character printed in a line or row may in an extreme instance be as great as twenty percent of the character height. The spacing of the characters along the line normally is held to closer tolerances but may vary depending upon the printing mechanism. Furthermore, in such equipment, it is possible to have variations in weight or uniformity of the lines forming the print, i.e., the print may be lighter or darker or the width of the line defining the character may vary, or the line may be spattered, due, for example, to the use of freshly inked ribbons. This type of variation compounds the difficulties encountered in character misregistration in making it more difficult to

2

determine the exact relative position of character line segments used in forming the over-all character.

As for the optical scanning of characters printed on ordinary stock quality of paper, the difficulty presented is that the paper may, due to spot variations in shading, appear non-uniform to the optical detector; or foreign particles in the paper stock may be erroneously considered as useful information or at least introduce appreciable noise into the system, thus interfering with the reliable reading of the character printed thereon.

The present invention overcomes the foregoing difficulties in reading characters printed on stock quality paper with conventional inking and printing equipment by providing novel circuitry and apparatus in an optical reading system which detects the location of a scanning device over predesignated portions of each of the characters in a row of print, for example, so that the character can be reliably read even though there are misregistrations or other variations in the print of the individual characters in the row. Furthermore, the present invention and approach provides a means and arrangement for scanning characters which permits a sufficiently large size scanning aperture to be employed such that, even if imperfections are optically detected in the paper, for example, the signal resulting from such imperfections is such a small percentage of the total spot being viewed by the scanner at any one time, that the noise introduced in the output signal is negligible.

Briefly, the present invention provides for reading characters which have been stylized such that when the character, as normally viewed, is divided into a plurality of vertical zones, segments of the lines forming the character appear in selected ones of, for example, the upper and lower halves of the vertical zones. These characters are printed in transverse rows on a tape, for example. A scanning device is provided for progressively scanning a row of characters, as the tape is moved. The movement of the scan across a row of characters is synchronized with a timing means whose outputs define the position of the scan along the vertical zones of the respective characters in a row. As the scanning of the row progresses, a record is maintained of the number of times the presence of each character is detected by the successive scans. Each time a character has been detected a predetermined number of times, the scanning device is positioned to scan across the upper and lower halves of the character. As the scan proceeds to read the character, the timing means is resynchronized for identifying the movement of the scan as it passes over the vertical zones of the character. The output waveforms provided by the scanning device have signals located in positions thereof identified by the timing means. These signals correspond to the locations of the line segments in the upper and lower halves of the vertical zones of the respective characters read.

It is an object of the present invention to provide an automatic character reading system having the foregoing features and advantages.

Another object of the present invention is to provide a system for reading a character by first locating a sensing means over a desired position of the character by counting the number of times progressive scans by the sensing means sense the presence of the character, and then reading out the signals sensed when the sensing means scans over the desired position of the character.

A further object is the provision of a system for reading a line or row of characters on a tape which system provides for synchronizing the outputs of timing circuits with the location of the scan along the row of characters by initiating or resetting the operation of the timing circuits in accordance with signals provided by sensing marks in predetermined areas of the tape.

Another object of the present invention is the provision of a system which is capable of reliably reading characters that have been printed by printing equipment having a relatively large permissible tolerance in the horizontal, vertical and skew misregistration of the printed characters relative to each other.

Another object of the invention is the provision of a system for reading printed characters wherein the weight or width of the line used in printing the character is permitted to vary.

A further object is to provide a character reading system which provides for obtaining information which defines a character printed on an ordinary stock quality of paper tape by scanning the character a plurality of times with a scanning detector whose sensing area is large relative to the size of spurious marks or defects that may be present in the paper.

Another object of this invention provides for reading characters which have been stylized such that the sensing of the position of the line segments forming the character, as obtained by simultaneous scanning of the upper and lower halves of the character, distinguish it from other characters in a group.

These and other objects and features of the invention will become apparent to those skilled in the art as disclosure is made in the following detailed description of a preferred embodiment of the invention illustrated in the accompanying sheets of drawings, in which:

FIG. 1 is a block diagram of a preferred embodiment of the invention;

FIG. 2 illustrates a section of a typical paper tape providing a record medium for printed characters to be read by the preferred embodiment of the invention;

FIG. 3 shows a section of the paper tape illustrated in FIG. 2 which has been considerably enlarged to facilitate the description of the invention;

FIG. 4 shows the typical forms of characters read by the preferred embodiment of the invention;

FIGS. 5a, 5b and 5c illustrate typical character lines and corresponding waveforms of signals produced during the operation of the preferred embodiment of the invention;

FIG. 5d is a block diagram of a peak detector;

FIG. 6 shows the subdivision of the area in which information representing a typical character is printed;

FIG. 7 shows a circuit diagram of the memory for the scan counter;

FIG. 8 is a block diagram of the clock setting circuit;

FIG. 8a illustrates certain typical signal waveforms for the circuit shown in FIG. 8;

FIG. 9 is a circuit diagram of a delay circuit used in the clock setting circuit;

FIG. 10 is a table used for explaining the mechanization of the trigger inputs of the character scan counter;

FIG. 11 is a combined schematic and circuit diagram of the character scan counter employed in the preferred embodiment of the present invention; and

FIG. 11a is a set of typical signal waveforms applied on a logic core of FIG. 11.

Referring now to the drawings, wherein like reference characters designate like or corresponding parts throughout the several views, there is shown in FIG. 1, which illustrates a preferred embodiment, a character reader including an optical detector 10 for scanning a tape 12 mounted for movement on a tape transport 14. As shown, a drive capstan 11 of the tape transport is coupled to a synchronous motor 13 to move the tape at a desired speed past the face of a forming head 19, which face defines the scanning station 17 for the tape.

An image of the section of the tape at the scanning station is formed by an optical lens 28 on the outer periphery of a rotating drum 20 included in the detector 10. In order that the image will be in focus for the entire length of a row of characters extending across the width of the tape, the curved face of the forming head

19 is made to conform to the curvature of the drum periphery, and the section of the tape at the scanning station 17 is maintained against the curved face of the forming head 19 by perforations leading to a vacuum chamber provided in the head.

5 The periphery of the rotating drum 20 is provided with four pairs of apertures, each pair designated 22a and 22b. The pairs of apertures are equally spaced about the drum periphery. The section of the periphery of the drum opposite the scanning station 17 is disposed to rotate past a viewing slot or window 23 provided in a stationary shroud 24 surrounding the drum. Two beam guides 26a and 26b, formed of Lucite rods, for example, are positioned adjacent the inner peripheral surface of the drum opposite the window 23 in the shroud. Changes in light level, produced as the image of a row of characters projected from the scanning station of the tape 12 is scanned by a pair of the moving apertures 22a and 22b, are transmitted through the respective beam guides 26b and 26a. As shown, the alignment of the drum 20 provides for movement of the pairs of apertures 22a and 22b in a direction which is perpendicular to the movement of the tape 12 past the scanning station 17. Thus, during operation, each pair of apertures of the optical detector 10 provides for simultaneous scanning of two laterally spaced sections of the image projected from the tape. It should be understood that the slot or window 23 in the shroud 24 covering the periphery of drum 20 is of such a size that the sides of the slot block light projected from the upper and lower edge portions of the tape 12, as viewed in FIG. 2, while passing a band of projected light which is adequate to transmit onto the drum periphery an image of at least one complete row of the printed characters on the tape.

35 The changes in intensity of the light entering the beam guides 26a and 26b, as the scanning progresses, are transmitted to respective photosensitive elements 30a and 30b. The photosensitive elements 30a and 30b are responsive to light variations to produce respective electrical signal outputs T₁ and B₁ which are fed into peak detector circuits 32. These circuits 32 produce shaped signals on outputs T and B, which signals precisely determine in time the centerline of lines or marks of the tape character images scanned by the optical detector 10.

45 The signals on each output T and B are produced in response to progressively scanning images of the character areas along the row of the tape. Each of these character areas is defined as a column of the tape. In order to assimilate the information on the outputs T and B of the optical detector 10, it is necessary to define 50 the operating position of the scan, i.e., the distance of travel of a pair of the moving apertures 22b and 22a, across the columns comprising a row of the tape, with respect to a reference mark provided for each row. This is accomplished by timing circuits comprising a sub-column counter 68 and a column counter 80, which counters effectively count clock or timing signals provided for the system. The outputs of the counters define the time position of the scan in the columns along the row on the tape.

60 In FIG. 1, the source of timing signals is shown to be a disc 36 mounted on a common drive shaft 35 with the drum 20. In a suitable arrangement, as shown, the clock signals are magnetically recorded on a track 33 located on the periphery of the disc 36 whereby a read head 37, located adjacent to the periphery of the rotating disc, is capable of detecting and reproducing the clock signals recorded on the track. The clock signals are coupled from the output of the read head 37 by way of a clock setting circuit 60 and an "and" gate 66 to the subcolumn counter 68. The disc 36 and drum 20 are driven by a synchronized motor 40 or similar constant speed motive driver, mechanically linked to the drive shaft 35. The linear speeds of the periphery of the apertured drum 20, timing disc 36, and tape 12 are

adjusted to provide the desired scanning rate for the detector 10.

Referring next to FIG. 2, a section of the tape 12 is shown having characters which are typical of characters read by the apparatus of the preferred embodiment. The characters are shown printed in rows across the tape, each row being divided into character areas or columns #1 to #8, inclusive. A first row 44 is typical of a complete row of characters in which no misregistration of characters is visibly noticeable and each character area or column is occupied by a character. It should be noted that a vertical line or reference mark 46 is located to the right of the characters in the row, i.e., adjacent the least significant character area or column #1. Preferably, the reference mark 46 extends vertically above and below the highest and lowest portions of the characters in the row so that during scanning, the optical detector 10 will detect the reference mark prior to detection of a line or mark of any character in the row as the detector scans from right to left across the tape. The reference mark 46 is always to the right of all of the columns or character areas in a row regardless of absence or presence of characters in character areas. A second row 48 on the tape 12, shown in FIG. 2, illustrates a group of characters having one character "4" misaligned vertically. The vertical misalignment of the character "4" is a typical misregistration which may occur as a result of misalignment of the character type during the ordinary process of setting up the type when printing the tape. A section of the tape including the characters "4," "2," and the reference mark 46 has been enlarged and shown in a separate view in FIG. 3, in order to illustrate further details of the preferred embodiment. Reference to FIG. 3 will be made in the ensuing description. A third row 52 of the tape shown in FIG. 2 illustrates misalignment in printing of a row of characters in the horizontal or transverse direction across the tape. Note here, that during printing the entire row of characters including the reference mark 46 had been shifted to the left. In actual practice, such a horizontal misregistration might not be so noticeable since it would be more apt to occur in a gradual manner and could result, for example, from a gradual slippage or movement of the tape to the right in the printer. A following row 54 on the tape illustrates a series of characters across the tape in which the least significant character area or column adjacent the reference mark 46 is unoccupied. It should be noted here, that the reference mark 46 retains its position in the row even though the adjacent character area is unoccupied in order that the column count will not be changed for the remaining characters in the row.

Referring back to FIG. 1, the timing circuits for defining the character columns of the tape will now be further described. Clock setting circuit 60 is provided for setting the clock signals, as received from read head 37, into phase with, for example, a reference signal T_R obtained by scanning the reference mark 46 provided at the beginning of each row being scanned. As will be explained in detail later in connection with FIGS. 8, 8a, and 9, this setting of the clock signal is accomplished by delaying the leading edge of the first clock signal C by a fixed period of time such that it will coincide with the leading edge of the output signal T_R produced by the reference mark 46. The clock setting circuit 60 operates after each such setting to delay all the following clock signals by a similar fixed period of time. Setting, i.e., delaying of the clock signals in this way, enables the subcolumn counter 68 and column counter 80 to locate the spatial area of the subcolumns and columns on the tape accurately, with respect to the row reference mark 46.

The setting circuit 60 is initially set to properly delay and gate out the clock signals in response to the triggering of the flip-flop G1 into the true state by output signal

T_R produced by optical detector 10 scanning the reference mark 46. The output signal T_R is selected from other signals on output T by an "and" gating circuit 70, which responds to signal T_R , and an initial reset signal K_R produced at the output of column counter 80. The output of the "and" gate 70 is coupled to the true trigger input g_1 of the flip-flop G1 via an "or" gate 74. As stated, setting of the flip-flop G1 into a true state initiates the clock setting circuit 60 to delay the clock signals C so as to generate clock signals C_s which coincide in phase with the output signal T_R generated at the beginning of a scan of a row of characters.

The subcolumn counter 68 is responsive to clock signals C_s to count through a cycle of 18 clock periods, which periods P_1 to P_{18} , inclusive, divide the area allotted to a column on the tape (see FIG. 3). The subcolumn counter 68, thus, counts 18 clock signals C_s received at its input to complete a cycle; and the next clock signal C_s serves to reset the subcolumn counter to P_1 to begin a new cycle. The subcolumn counter 68 is provided with individual outputs $P_1, P_U, P_V, P_W, P_X, P_Y, P_{17}$, and P_{18} , which outputs have signals thereon only when the counter actually resides in the count indicated thereby.

In FIG. 3, showing a portion of tape 12, the printing area corresponding to each column of the tape is shown divided into transverse zones including U, V, W, X, and Y. The width of each of these zones with respect to time is equal to three clock periods. For example, zone U corresponds to P counts P_2, P_3 , and P_4 . Thus, the individual signal outputs P_U, P_V, P_W, P_X , and P_Y of the subcolumn counter 68 correspond to and define the spatial operating position of the scan when in these respective zones of the column. The additional signal outputs P_1, P_{17} , and P_{18} of the subcolumn counter 68 locate the spatial operating position of the scan with respect to the reference mark 46 on the tape, such that other functions can be performed during these P counts of each cycle of the subcolumn counter, as will be set forth in detail later on in the description.

The column counter 80 is advanced once each cycle of the subcolumn counter 68, at the same time the latter resets to count P_1 , to count through eight successive counts K_1 to K_8 , respectively, indicative of the scanning periods of the columns #1 to #8 in a row. The column counter is also provided with initial reset states K_S and K_R , indicative of periods prior to scanning of the columns of the tape. State K_S defines the period during which the pair of apertures 22a and 22b, next to scan the image, are still behind the shroud 24; and state K_R defines the period from the instant these apertures pass from behind the shroud into the area of the window 23, and up to the beginning of the area on the tape allotted to column #1.

Referring again to FIG. 3, a description of the circuits in FIG. 1 will be continued by following the operation as the character or column areas are scanned. It should be assumed that the scanning sweeps of the image projected from the tape, by the pairs of moving adjacent apertures 22a and 22b of optical detector 10, have progressed to the sweep indicated, generally in FIG. 3, by horizontal paths 88 and 89, respectively. It should be noted at this point that only the information produced by the scan of apertures 22a are used prior to the "read" scan for a character, hence, only the scan along path 88 is of interest at this time. As the scanning progresses along path 88 from right to left across the tape, signals on output T are produced by the detector 10 in response to the significant changes in the intensity of the projected light from the area of the tape being scanned.

The first abrupt change in intensity of the light is detected as an aperture 22a in the rotating drum 20 moves upward from behind the bottom edge 92 of the window 23 in shroud 24. Signal output T_S produced in photosensitive element 36a by this abrupt change in intensity of light is coupled to an "and" gate 84 provided at the

input of the column counter 80. Prior to this time, the column counter 80 is in its idle state, providing an output signal K_S , which signal is also coupled to the "and" gate 84. The output signal T_S combined with signal K_S produces a signal on the output of gate 84 which passes through an input "or" gate 86 of the column counter 80, whereupon the column counter is advanced to state K_R .

As the scanning progresses further along path 88 across the tape, the reference mark 46 is next detected through the same moving aperture 22 t , and an output signal T_R is produced. Signal output K_R of the column counter 80 now combines with signal T_R in an "and" gate 70 to provide a signal which passes through "or" gate 74 to input g_1 of flip-flop G1, triggering this flip-flop into its true state. The output G_1 of this flip-flop is coupled to the clock setting circuit 60 to initiate its operation. The clock signals C_s , provided on the output of the setting circuit 60, are coupled through gate 66 to the input of subcolumn counter 68 to advance the count.

During the period defined by signal K_S of column counter 80, and "and" gate 94 connects the output signal T_S produced in the detector 10, into an input of the subcolumn counter 68, to reset this counter to count P_{13} . Referring momentarily to FIG. 3, it will be noted that count P_{13} corresponds to the area allotted to the centerline of the reference mark 46. After being reset to count P_{13} , the subcolumn counter 68 is responsive to the next five clock signals C_s to advance to count P_{18} . On the next clock signal C_s , the subcolumn counter resets to count P_1 of a new cycle, and the column counter 80 is advanced to count K_1 , indicating that column #1 of the tape is next to be scanned.

As the scan indicated by path 88 progresses across column #1 of the tape, it should be noted that the character "2" printed thereon is not traversed by the scan and the subcolumn counter 68 merely advances on successive clock signals C_s to count P_{18} to complete the counting cycle for the column. The subcolumn counter 68 then begins a new cycle on the next clock signal by resetting to count P_1 , and the column counter advances to count K_2 , indicative of scanning column #2.

As the scan progresses transversely across column #2 of the tape 12, the scan along path 88 for the first time crosses a character mark in zone U, during signal period count P_2 . The optical detector 10 is responsive to the mark in the zone U to produce, via peak detector circuits 32, an output signal T_C which is coupled to the true trigger input a_1 of flip-flop A1, triggering the flip-flop into its true state. It should be noted that flip-flop A1 was triggered into its false state at P_{17} of the previous cycle of the subcolumn counter.

As the scan along path 88 continues to advance to the left in column #2, the optical detector 10 senses the mark in zone W of the character "4." This second output signal T_C produced by the light passing through aperture 22 t of the detector 10 during this particular scan of column #2 is coupled from the peak detector circuits 32 to the true trigger input a_1 of the flip-flop A1. Since the flip-flop A1 has already been triggered into the true state in response to the character mark in the subcolumn zone U, this second output signal T_C produced by the character mark in the subcolumn zone W has no effect on the state of this flip-flop.

As the scanning continues to move to the left across column #2, along the path 88, the count of the subcolumn counter continues to advance through counts P_{11} to P_{16} for the subcolumn zones X and Y. The signal representing count P_{17} is coupled along with signal A_1 to an "and" gate 96 whose output is fed into an "or" gate 97 to advance a character scan counter 100 from its zero count S_0 to its one count S_1 .

The signal output P_{17} is also coupled to an input g_1 of the flip-flop A1 to trigger the flip-flop into its false state in preparation for sensing a character mark in the next column, column #3 of the tape.

It should now be clear that since no portion of the character "2" in column #1 was traversed by the scan along path 88, no record was made of this scan in scan counter 100. However, since the character "4" in column #2 was traversed by the scan along path 88, the scan counter 100 made a record of this scan count at count P_{17} , and the scan along path 88 thus became scan 1 for the character "4" in column #2.

Continuing with the operation during the cycle allotted to column #2, on the next clock signal the subcolumn counter is advanced to its final count P_{18} . The signal output P_{18} serves to open an "and" gate 102 which transfers signals from the scan counter 100 indicative of the scan count S_1 for the column #2, into a section of a scan counter memory 104. The section in the memory in which the character scan count is stored is selected, in this instance, by the column counter signal output K_2 which is coupled to the memory 104. The scan counter memory 104 is further described in connection with FIG. 7.

On the next clock signal, the subcolumn counter 68 is reset to count P_1 and the column counter 80 is advanced to count K_3 indicating that column #3 of the tape is next to be scanned. As the scan along path 88 continues across the remainder of the columns in the row of characters, the column counter 80 is advanced at the beginning of each new cycle of the subcolumn counter 68. If the scan along path 88 touches a portion of the character in any of these subsequent columns, the character scan counter 100 is advanced to count S_1 during P_{17} of the scanning of the respective column, and the information is stored in a section of the memory 104 during the clock period corresponding to count P_{18} of the subcolumn counter 68.

At this point, it may be noted that the memory 104 for the scan counter 100 is interrogated during each count P_1 clock period of a cycle of the subcolumn counter in order to reset the scan counter 100 with the scan counts so far accumulated for each column by the previous scans.

The column counter 80 selects the position in the memory 104 in which the scan count for column presently to be scanned, is stored, and the accumulated scan count stored therein is transferred into the character scan counter 100. The scan count is transferred during count P_1 of the cycle from the memory 104 through a set of "and" gates 108 to set the character scan counter 100 at the proper count for the individual column to be scanned in the remainder of the cycle of the subcolumn counter.

At the end of the subcolumn count for column #8, for the scan along path 88, the subcolumn counter is reset to P_1 to start counting a new cycle and an overflow signal from the subcolumn counter 68 is coupled to the column counter 80 resetting the latter to the idle state K_S .

The signal output of the column K_S is coupled to the false trigger input g_1 of the flip-flop G1 to trigger this flip-flop into a false state. The output signal G_1 is coupled to the clock setting circuit 60 to discontinue its operation and prepare it for setting the clock signals again, in accordance with the next output signal T_R .

The clock signal C is blocked from passing the "and" gate 66 at the instant flip-flop G1 triggers to the false state. With the clock pulses C blocked, the subcolumn counter is inactive and the column counter remains in its idle state K_S until the edge 92 of the shroud 24 is crossed by the next aperture 22 t of the drum to effect the next scanning sweep, indicated generally in FIG. 3 by the path 106. The output signal T_S , produced by the detector sensing edge 92 of the window 23, causes the subcolumn counter 68 to be again reset to count P_{13} via "and" gate 94. This signal T_S is also coupled to the "and" gate 84, as described in the previous scan along path 88. The signal output of the "and" gate 84, which is coupled to the column counter 80 input, advances the column counter to state K_R .

The next output signal T_R produced in response to the

output of the optical detector as the reference mark 46 is scanned, is coupled to the flip-flop G1 to set the clock signal to coincide in phase with the output signal T_R . The output of clock setting circuit 60 is passed through the gate 66 to the input of the subcolumn counter 68, advancing its count from count P_{13} to indicate the spatial operating position of the scan from the midline of the reference mark to the beginning of the column #1.

As the scan along path 106 crosses over into column #1, the subcolumn counter 68 is reset to P_1 for a new cycle and the column counter is advanced from state K_R to count K_1 . As the scan progresses transversely across column #1 of the tape, along the path 106, the detector 10 this time senses a character mark in zones V, W, and X defined by pulse periods P_5 to P_{13} , inclusive. The output signal T_C produced by the detector 10 in response to the mark is coupled to the flip-flop A1 to set it in the true state indicating that the character in column #1 has been detected. During count P_{17} , in combination with signal A1, the "and" gate 96 is open, and the scan counter is advanced to count S_1 since the scan count for this column #1 was previously zero. During the next clock period, count P_{18} of the subcolumn counter, "and" gate 102 is opened to transfer the scan count S_1 for column #1 into the section of the memory reserved for this scan count, as selected by count K_1 .

On the next clock signal, the subcolumn counter is reset to count P_1 and the column counter is advanced to count K_2 , indicative of scanning column #2. The signal output K_2 of column counter 80 is coupled to the scan counter memory 104 for selecting the section of the memory corresponding to column #2 in which the scan count from the previous scanning sweep along path 88 has been stored. The signal output P_1 from the subcolumn counter opens an "and" gate 108 to transfer the scan count S_1 , the scan count stored in the memory for column #2, into the character scan counter 100.

As the scan progresses past the character mark in zone U of column #2, an output signal T_C is produced which is coupled to the true trigger input a_1 of the flip-flop A1. As the scan continues, it also intercepts the character mark in zone W and another output signal T_C is produced which is also coupled to the true trigger input a_1 of flip-flop A1. However, since the flip-flop A1 has been set in its true state by the previous output signal T_C , the second pulse has no effect.

The scan continues to advance across the tape without detecting other character marks in column #2. At count P_{17} , the true state of the A1 flip-flop indicates that the scan along path 106 transversed the character at least once during the current scanning sweep and hence the scan counter is advanced to count S_2 . The flip-flop A1 is triggered into its false state at P_{17} time so as to be in the proper state to indicate whether or not a character in column #3 is traversed by the scan in the current scanning sweep during the next cycle of the sub-column counter.

In the next clock period, P_{18} , of this scan in column #2, the scan count S_2 is stored in the section of the memory reserved for the scan count of column #2, which section is selected by the signal output K_2 .

As in the previous scanning sweep, the remainder of the character areas or columns in the row are scanned along the path 106, and a record is transferred to the memory 104 indicative of the respective scan counts. After the scan advances past the last column, column #8, the column counter is advanced to its idle state K_S and the signal K_S triggers the flip-flop G1 to its false state, blocking the input of clock signals C_s to the subcolumn counter.

On the next scanning sweep, indicated by the path 110 in FIG. 3, an output signal T_S is produced, as before, by the detector upon scanning the edge 92 of the shroud 24. The output signal T_S , coupled to column counter 80

through the gate 84, advances the column counter to the count K_R .

As in the previous scanning sweeps, the reference mark 46 is detected as the scan advances across the tape, and clock signal C_s is set to coincide with the output signal T_R , and the subcolumn counter, which has been reset to count P_{13} , is advanced on to the end of its cycle.

Upon resetting the subcolumn counter to count P_1 , the column counter is advanced to count K_1 , indicative of scanning column #1. Also, during count P_1 the scan count S_1 , for column #1 as stored in memory 104, is transferred, via gate 108, to the scan counter 100. During the scanning of column #1 along path 110, the flip-flop A1 is triggered into its true state in response to an output signal produced by the detector in scanning the character marks. At count P_{17} , for column #1, the character scan counter 100, in recognition of the true state of flip-flop A1, is advanced to count S_2 . In the subsequent count, P_{18} , the count S_2 is stored in the memory 104.

During scanning in column #2, along path 110, the scan count S_2 is transferred to the scan counter 100 during time P_1 . When character marks are detected along the scan, as shown in FIG. 3, the flip-flop A1 is triggered into its true state. At count P_{17} , the signal output S_2 from the scan counter 100 serves to open the "and" gate 112 to permit the signal output P_{17} to pass through an "or" gate 114 to the input f_1 of the flip-flop F1. The flip-flop F1 is triggered into its true state providing a true output signal F_1 , which signal, as will be clearly explained in the subsequent description, is evidence that the next scan of this particular character is the "read" scan.

Continuing with the scan in column #2, as in the previous scans, the true signal output A_1 of the flip-flop A1, indicating the character was traversed, is coupled to the character scan counter 100 to advance, during count P_{17} , the scan count to S_3 ; and in the next clock period P_{18} , the scan count S_3 is stored in the memory 104. In addition to storing the scan count, the F_1 signal, indicative of the true state of the flip-flop F1, is stored via the "and" gate 102 during count P_{18} in the scan counter memory 104. After the remainder of the columns are scanned, and the scan counts for the respective columns stored in the memory, the column counter 80 is advanced to K_S .

On the next scanning sweep of the row of characters by the following pair of apertures 22*a*, and 22*b*, which scanning sweep is generally along the respective paths 116 and 117, the edge 92 of the shroud 24 is detected, as before, through aperture 22*a*, and the column counter is advanced, via gates 84 and 86, to state K_R , in which state it is awaiting the detection of the reference mark 46 of the row. Upon detection of the reference mark 46, a clock signal is set to coincide with the output signal T_R and the subsequent clock signals C_s are applied to the subcolumn counter through the "and" gate 66. As in previous scanning cycles, the subcolumn counter has been reset so as to advance from count P_{13} , which is the spatial position with respect to time of the midline of the reference mark 46. Upon the scan entering column #1 along path 116, the subcolumn counter is reset to count P_1 while the column counter advances from state K_R to state K_1 . During the first signal period, count P_1 of column #1, the scan count S_2 for column #1 is read out of the memory and routed to the character scan counter 100 through the gate 108, setting the scan counter to the previous scan count S_2 for column #1. As the scan progresses across the vertical zones of the column #1, it again crosses character marks to set the flip-flop A1 into its true state. At count P_{17} , the signal output S_2 opens the "and" gate 112 to pass the signal output P_{17} to the input f_1 of flip-flop F1 triggering the flip-flop F1 into its true state. The character scan counter is advanced to count S_3 and the flip-flop A1 is returned to its false state during the next signal period, count P_{17} . During the time period P_{18} , the character scan count S_3 for column #1 and the F_1 signal indicative of the true state

of the F_1 flip-flop, is stored in the scan counter memory 184.

The continuation of the scan along path 116 into column #2 is the "read" scan for column #2, i.e., the time during which the transverse position of character marks in top and bottom portions of the character as scanned by both apertures 22*a* and 22*b* of detector 10 are detected and stored in the top register 120 and the bottom register 122 in two five-digit codes, respectively, representing the character. Consequently, the character marks in path 116 are scanned by aperture 22*a* and the character marks in path 117 are scanned by aperture 22*b* during this "read" scan.

On entering column #2, the subcolumn counter 68 is reset to count P_1 and the column counter 80 is advanced to count K_2 indicative of scanning column #2. The output signal P_1 is coupled to the "and" gate 108 to transfer the scan count S_3 for column #2 from the memory to the scan counter, and to reset the flip-flop F_1 to its true state, as stored in the memory in the previous scanning sweep of column #2.

The output signal F_1 opens "and" gates 124 and 126 which are connected to the respective inputs of top register 120 and bottom register 122. The signal F_1 is also coupled to open the "and" gate 128*a* to pass the signal P_1 through an "or" gate 130 to the false trigger input, g_1 , of flip-flop G1. With flip-flop G1 in a false state, the gate 66 feeding clock signals C_s to the subcolumn counter is blocked, and the dock setting circuit 60 is prepared for resetting in response to a new output signal T_C or B_C applied on an input "or" gate 132, which connects via "and" gate 134 "and"/"or" gate 74 to the true trigger input g_1 of the flip-flop G1.

During a "read" scan for a character, in order to compensate for possible horizontal misregistration of a character in a column and synchronize the timing of spatial position of the character marks precisely within their allotted zones of the column, the clock setting circuit is set for the "read" scan of each character to the first character mark which is detected by either the top or 35 bottom read scan. As the scan, along path 116, progresses across column #2, with the subcolumn counter no longer receiving clock signals C_s , both top and bottom scans intercept the character mark in the zone U.

It should be noted (FIG. 4) that all characters are stylized to have a character mark in at least either the top or bottom portions of the U zone. These output signals T_C and B_C are coupled to the true trigger input g_1 of the flip-flop G1 through the "or" gate 132, and the "and" gate 134, opened by the "read" scan indicating signal F_1 , and finally the "or" gate 74. In this manner, the output signals T_C and B_C trigger the flip-flop G1 into its true state to provide a signal output G_1 which is coupled to the clock setting circuit to set the phase of the clock signals coincident with either of the output signal T_C and B_C , whichever happens to be present.

The signal output G_1 is also effective to pass the clock signals C_s through the gate 66, to again permit the subcolumn counter 68 to advance. During the cycle of the subcolumn counter that the "read" scan occurs, the subcolumn counter, upon being inactivated at P_1 , is reset to count P_3 by signals F_1 and P_1 applied on "and" gate 138. In the foregoing manner, the signal T_C or B_C as sensed by a character mark in the U zone, is utilized to trigger flip-flop G1 into a true state to initiate the clock setting circuit 60 to advance the subcolumn counter from its P_3 count. In this way, the centerline of the character mark in the zone U is synchronized with the P_3 count irrespective of whether or not the character mark in the U zone is accurately positioned with respect to the reference mark 46.

As shown in FIG. 1, the output signals T_C and B_C , after passing through "and" gates 124 and 126, as opened by signal F_1 , are coupled to the top and bottom registers 120 and 122, through individual "and" gates 127 and

128, respectively. Initially, the top and bottom registers, each of which has five storage sections, as shown, are reset to store digits "0" throughout. The count signals P_U , P_V , P_W , P_X , and P_Y of the subcolumn counter 68 are coupled to successively open gates 127 and 128 of the respective bit storage sections of the top and bottom registers to locate and route signals T_C and B_C into respective bit storage sections of these registers, changing each sections when a signal is present to store a digit "1." Thus, a first section in each of the top and bottom registers is selected by the signal P_U to store the respective information signals T_C and B_C detected in the U zone of the character being scanned; a second section in each of these registers is selected by the signal P_V to store the respective information signals T_C and B_C detected in the V zone of the character being scanned; and remaining sections in each of the registers are selected by the signals P_W , P_X , and P_Y to store the respective signals T_C and B_C detected in the respective W, X, and Y zones of the character.

In the scanning of the character "4," shown in FIG. 3, during the "read" scan, the T_C and B_C signals, detected by transversing zone U of the character, are stored during signal P_U as binary digits "1" in respective first sections of the top and bottom registers. No signals T_C and B_C are detected upon traversing zone V and hence, the second sections of the top and bottom registers during signals P_V remain unchanged, indicative of storing binary digits "0." Upon traversing zone W, only a signal T_C is produced, and hence, the third section of the top register during signal P_W is provided with a binary digit "1," while the third section of the bottom register is left with a binary digit "0" stored therein. Upon traversing zones X and Y, no signals T_C and B_C are produced and hence, the fourth and fifth sections of each of the top and bottom registers are left with binary digits "0" stored therein. Thus, as a result of the "read" scan of character "4," the top register is storing the five-bit binary code 00101, and the bottom register is storing the five-bit binary code 00001.

Continuing with the "read" scan cycle for column #2, on count P_{17} , the character scan counter is advanced to scan count S_4 by application of the signal output P_{17} to the scan counter input through gate 96. In addition, the signal P_{17} is applied to the flip-flops A1 and F1 to trigger them into their false state. The false trigger input g_1 of the flip-flop F1 is connected to the output of an "and" gate 140 opened to P_{17} by the signal F_1 . During the following clock period, count P_{18} , the scan count S_4 is stored in the memory.

During this count P_{18} , of the "read" scan, as evidenced by scan count S_4 , the coded information stored in each of the respective sections of the top and bottom registers 120 and 122, respectively, can be routed for storage into a buffer register (not shown) for subsequent use in a data processor. Or as shown in FIG. 1, the information in the sections of the registers 120 and 122 can be simultaneously fed, along with signals P_{18} and S_4 into a decoder 142, which decodes the information such that the appropriate one of the output leads 109 from the decoder has a signal thereon indicative of the character read, in this instance the character "4."

In order to identify the character read with the column of the tape in which it is printed, the output leads 109 may be connected in parallel to eight sets of "and" gates 105. Each set of these gates is connected to be opened by a respective one of the signals K_1 to K_8 , to provide for the respective columns a signal indicative of the character read. Thus, in this instance, the character "4" is fed out of one gate of the set of gates 105 opened by signal K_2 . Visual indicators 163, may be provided at the output of each set of gates 105 to visually display the characters read in the same sequential location they have on the row of the tape. After the character "4" in column #2 is read out, the scan continues along paths 116 and 117 of the remaining channels of the row, resulting in

merely advancing the scan count or in reading out a character, dependent on the number of scans so far detected for each character.

On the following scanning sweep, indicated by the paths 118 and 119, the column counter 80 is advanced to the state K_R from the idle state K_S , in the same manner as in previous sweeps, to prepare for scanning past the reference mark. As described supra, the clock signals are set in phase to the output signal T_R and the subcolumn counter is reset to P_{13} . As the scanning proceeds into the character area of column #1, the subcolumn counter is reset to count P_1 and the column counter is advanced to count K_1 . The sequence of operations, from this point forward in the "read" scan of column #1, is similar to the "read" scan for column #2. Thus, during the first clock period, count P_1 of column #1, the clock signals are blocked at the gate 66, as the flip-flop G_1 is triggered into its false state, and the subcolumn counter is reset to P_3 . Furthermore, during P_1 , the scan counter 100 is set with the information stored in the memory for column #1, i.e., scan S_3 , and the flip-flop F_1 is set to a true state in accordance with information stored in the memory. Continuing with the progress of operations, during the "read" scan of column #1, as the bottom scan along path 119 intercepts a character mark forming a portion of a character "2" in zone U of column #1, an output signal B_C is produced which is coupled to the flip-flop G_1 to trigger it into its true state. The signal G_1 then initiates the operation of the clock setting circuit 69 to reset the clock signals. The information signal B_C is coupled to the bottom register 122 in a section or position selected by the signal P_U , causing a binary digit "1" to be stored therein. Since no T_C signal is present, the position in the top register 120 selected by signal P_V is left in its initial state with a binary digit "0" stored therein.

As the scan crosses into zone V, the top scan intercepts the character mark forming the upper portion of the character "2," and the bottom scan simultaneously passes over an area in zone V which does not contain a character mark. The signal T_C produced by the circuit 32 in response to the character mark in the top portion of zone V is coupled to the top register 120 through the gate 124. The position in the top register corresponding to zone V is selected by the signal P_V of the subcolumn counter, and is changed to indicate a binary digit "1." Since the lower or bottom scan did not intercept a character mark in zone V, there was no signal B_C and the state of the selected position in the bottom register is left storing a binary digit "0."

The scan next passes through the vertical zone W without intercepting a character mark. The output signal P_W of the subcolumn counter is coupled to the top and bottom registers to select positions in the register for any information output signal T_C or B_C of the detector. However, since no signals are produced in zone W, the positions corresponding to this zone in the registers are left storing a binary digit "0." The simultaneous scanning next advances to vertical zone X wherein both top and bottom scans intercept character marks. The information signals T_C and B_C , produced by the detector in response to the character marks are stored as binary digits "1" in the top and bottom registers, respectively, in positions selected by the signal output P_X . The scan next crosses into vertical zone Y and since no character marks are present in this zone, the corresponding positions selected by count P_Y in the top and bottom registers 120 and 122 are not changed in state, remaining with binary digits "0" stored therein. During the following clock pulse period, count P_{17} , the flip-flop F_1 is triggered into its false state by signal P_{17} which is passed by the "and" gate 140 opened by the signal F_1 . Thus, during the "read" scan of column #1, the position of character marks in the respective zones of the column, as traversed by the "read" scan, are detected, translated and stored

in the top and bottom registers 120 and 122 according to their positions to provide two five-digit binary codes 01010 and 01001, respectively, representing the character "2."

- 5 The signal P_{17} is passed through the gate 96, opened by the output A_1 , to the input of the scan counter to advance the count therein to count S_4 . The signal P_{17} , is also coupled to the input a_1 of the flip-flop A_1 to reset it into its false state to prepare for triggering by signals 10 T_C during the scanning of the following column.
- 10 During the next clock period, which represents the last clock period of the "read" scan, the signal P_{18} along with signal S_4 is coupled to decoder 142 to decode the two five-digit binary codes representing the character, as stored in the top and bottom registers 120 and 122, respectively. The decoder 142, as previously described, provides a signal on one of the output lines 109 which corresponds to the character decoded, in this instance the character "2". As previously described, the character "2" for column #1 can be gated by signal K_1 to be displayed by visual indicator 103, as shown. During this same clock period, P_{18} , gate 102 is opened to pass the character scan count S_4 for column #1 into the scan counter memory 104.
- 15 As the scan enters column #2, the subcolumn counter is recycled to count P_1 and, as in previous cycles, a carry signal is provided which is coupled to the column counter 80 to advance the count to K_2 . While scanning the tape in column #2 during the first clock signal period, P_1 , the count stored in the scan counter memory 104 is transferred to the scan counter through the gate 108 to set the scan counter to count S_4 . Thereafter, the scan enters the zone U, intercepting the character mark simultaneously with both top and bottom portions of the scan.
- 20 The output signal T_C , produced by the detector 10 in response to the character mark, is coupled to the true trigger input a_1 of the A_1 flip-flop, triggering the A_1 flip-flop into its true state to provide an output signal A_1 . The scanning continues across the remainder of the column #2 and on count P_{17} of the subcolumn counter, the character scan counter is advanced by the output signal A_1 , opening "and" gate 96 which passes a signal through the "or" gate 97 to advance the scan count to S_5 . On count P_{18} , this scan count S_5 is stored in the scan count memory 104.
- 25 It should be noted that to ensure counting the scans after the first two scans of a character have been recorded, an "and" gate 98 is provided which passes a signal at count P_{17} if any of the signals S_2 to S_{12} are present.
- 30 In other words, after scan S_2 has been recorded for a character, even if a mark is not observed, the scan count is advanced. In the preferred arrangement, the scanning of the row of characters on the tape is repeated as above until each character area is scanned twelve times. After the twelfth scan, S_{12} , the scan counter is recycled to S_0 .
- 35 On scanning sweeps between rows of the tape, the column counter is advanced to state K_R by the output of the "and" gate 84 which responds to signals T_S and K_S . In addition to advancing the column counter 80 to state K_R , the output of gate 84 actuates a multivibrator D1. The multivibrator D1 is a "one shot" which is normally in a false state with the output D_1' therefrom having a signal thereon. When the multivibrator is triggered into a true state by the output of gate 84, it will remain there for a fixed period of time, and then automatically return to its false state. The output D_1' is connected into an "and" gate 152 along with signal K_R . A signal from gate 152 is effective to reset the column counter back to K_S .
- 40 The minimum time interval provided for the delay in multivibrator D1 is the maximum time required for the reference mark 46 to be detected if it is in the path of the scan. For example, the time delay provided for returning the multivibrator D1 to its false state, in the preferred arrangement, is a time interval equal to the

- 50
- 55
- 60
- 65
- 70
- 75

time allotted to scanning a column, i.e., 18 clock periods.

During the operation of the multivibrator D1, in the event a reference mark T_R is not detected in the path of the top scan, i.e., the scanning sweep is between rows, the column counter will remain in state K_R . After the delay period of the "one shot" multivibrator D1, its output signal D_1' along with signal K_R provides an output signal from the "and" gate 152, which operates to reset the column counter back to the state K_S in preparation for the following scanning sweep of the tape. Therefore, if the column counter is still in state K_R at the end of the time interval of the "built-in" delay of the multivibrator D1, the automatic restoring of the multivibrator D1 to its false state causes the column counter to be reset to the K_S state. If no provision were made for resetting the column counter to the K_S state, in the absence of the sensing of a reference mark, any mark or imperfection anywhere in the scan along the row of the tape could be erroneously detected as a reference mark, and advance the column counter to count K_1 . In the event that no improper mark or imperfection were present on the tape, the leading edge of the shroud, on the next scanning sweep, might erroneously actuate the circuitry in the same manner as a reference mark, causing the circuits to operate with incorrect timing.

In discussion of the "read" scan, it was noted that each character is distinguished by its pattern of character information or marks in the top or bottom scan portions of the vertical zones U, V, W, X, and Y allotted to the character area on the tape. Further, the scan information is translated into the form of two five-digit binary codes representing the characters. In FIG. 6, the five coded zones are illustrated for the character "2." The top "read" scan area of the zones and the bottom "read" scan area of the zones, respectively, define the extent of variation that the path of the top and bottom apertures 22a and 22b could have across the character, and still produce the desired distinguishing signals T_C and B_C in the respective outputs of the detector circuit, so that these signals can be stored in the top and bottom registers 120 and 121, respectively, in accordance with the count signals P_U , P_V , P_W , P_X , and P_Y , to provide the two five-bit binary codes shown adjacent the output signals T_C and B_C , in FIG. 6.

The permissible top and bottom "read" scan areas include a substantial portion of the top and bottom halves of the characters. In view of the ample tolerances provided, it is immaterial to the reading of a character whether or not a scan, in which only a fragment of the upper tip of the character is detected, is counted as the first scan, since the position of the "read" scan (the fourth counted scan) can vary in the top and bottom halves of the character without affecting the accuracy of reading the character. Further, by providing an ample tolerance for the "read" scan, the reading of a character is not seriously affected by slight variations in the normally constant speed of the tape by the tape handling mechanism, variations in over-all heights of the characters due to the weight of the marks or lines forming the characters, vibrations and irregularities in the speed of the scanning drum, or minor variations in the size and spacing of the scanning apertures.

In FIG. 4, typical digit characters "0" through "9" and alphabetical characters "B," "F," "M," and "T" which are stylized to be read by the apparatus of the present invention are shown along with the corresponding top and bottom five-digit binary codes representing the characters respectively. Each character is shown divided into the five vertical zones U, V, W, X, and Y in which character information, in the form of vertical segments or lines used in forming the character, is positioned. The horizontal paths designated r_t and r_b passing through top and bottom halves of the character, respectively, such as character "0," indicate the location of typical top and bottom sensory traverses which would intercept segments

of the character to provide the character information in the form of pulse position modulated signals which are necessary to translate the character. It should be clear from FIG. 4, that the characters are stylized such that a portion of the vertical lines or segments forming the character is positioned in at least the top or bottom transverse areas of zone U for the "read" scan of each of the characters. Preferably, as shown in FIG. 4, the top vertical line segments of the character are not disposed in adjacent vertical zones and the bottom vertical line segments are not disposed in adjacent vertical zones. The groups of signals derived from the individual sensory traverses of the segments of the character in top and bottom transverse areas individual to each character are pulse position modulated signals or pulse time modulated signals representing respective characters. The leading edge, i.e., the line segment of a character which is intercepted first by a sensory traverse during a "read" scan, provides the time reference for the position modulated signals for the character and the signals are positioned in time relative to the time reference to provide the position modulated signals representing individual characters.

In FIG. 5a, a typical character image mark or line segment 160 is shown along with corresponding waveforms produced within the detector circuits 32 to provide a typical signal T_C . Upon the scanning of a vertical line portion of a character represented by mark 160 by the optical detector, the photosensitive element 30t, for example, provides a signal waveform 162. This signal waveform is coupled to the input of peak detector circuit 32. As shown in FIG. 5d, the peak detector circuit includes an amplifier 155 which amplifies the input waveform 162 and adjusts its clipping level to eliminate noise, as shown by the signal waveform 164. The signal waveform 164 is then differentiated in differentiating circuit 156 to provide a signal waveform 165. The negative-going portion of the signal waveform 165 is next amplified in amplifier 157 and then coupled to the input of a blocking oscillator 158, wherein the signal is reformed from the negative side of the base line crossing, as shown in FIG. 5a, to produce the output signal T_C .

In FIG. 5b, typical printed marks or lines are illustrated which form characters in the ordinary process of printing. A single, heavy line 163 is detected by the detector circuits to produce a signal waveform 170 which is coupled to the peak detector circuits to produce a differentiated waveform 172 and an output signal 174. A pair of character lines 176 are shown as heavy and spaced relatively close and hence, because of their spacing, upon detection they produce a slightly distorted signal waveform 178. This signal waveform 178, when differentiated, produces a typical signal waveform 180. This latter waveform is amplified and reformed to produce a pair of output signals 182. Thus, by means of the peak detection circuit 32, clearly distinguishable output signals are produced in response to closely spaced, heavily inked lines.

A lightly inked character image line 184 is shown along with corresponding waveforms produced in the detector circuits. Although the signal waveform 186 is lower in amplitude than signal waveforms 170 and 178, the output signal 188 is of the same amplitude as output signals 174 and 182. Thus, the detector circuit provides uniform character information output signals for translation in the translator circuits.

In FIG. 5c, varying width character image lines 190, 192, and 194 are shown being scanned by the same size aperture 22t provided in the scanning drum. As the aperture, such as the aperture 22t, passes light from an image of character line 190, a signal waveform 198 is produced in the detector circuits. Since the aperture 22t is narrower than the transverse dimension of the character line 190, the signal output of the photosensitive element 30t detecting the light variations tends to flatten out on top during the time interval the aperture is completely oc-

cupied by the light forming the character image. However, due to the darker inking in the middle of the character line, a gradual peaking is observed.

The same sized aperture 221 upon scanning the narrow character line 192 will produce an output in the detector circuits which reaches a certain level and tends to flatten out for the time interval all of the aperture is receiving light reflected from the image 192. Some ink will darken the area immediately adjacent the narrow line which will produce the gradual peaking of the output signal 200. The next character mark 194 scanned by the aperture 221 is substantially the same width as the aperture, and, since the aperture is completely occupied by the light from the character mark for only an instant, the signal waveform 202 is produced by the photocells and coupled from the output to the peak detector circuit 32. The width of the character mark 194 is the average width of character marks or lines produced in the ordinary course of printing journal tapes, with a particular type. In the preferred arrangement, therefore, the size of the aperture, that is, the transverse dimension, is preferably designed to be the average width of the vertical printed lines produced by the particular character type. In this manner, the output signal of the detector is readily shaped by peak detector circuit 32 to provide suitable output signals T_C or B_C .

It should be noted that the scanning aperture 221 is made to be sufficiently large in size such that if imperfections or undesirable markings on the paper tape, not representative of reference or character lines, should be detected while scanning the image projected from the paper tape, the signals resulting from these spurious marks represent such a small percentage of output signal produced by the total area viewed through the aperture that the noise introduced thereby in the output signal is negligible.

Before describing the detail arrangement of the clock setting circuit 60 shown in FIG. 8, the details of an adjustable delay circuit, such as the circuit 205 shown in block form in FIG. 8, will be presented. As shown in FIG. 9, this circuit includes a multi-apertured core 250 having a high residual magnetism and a substantially rectangular hysteresis characteristic. The core 250 is provided with a major aperture 254 and a minor aperture 259. A "clear" signal winding 251 and a "set" signal winding 252 are wound about a leg of the major aperture 254, and an input signal winding 256 and a "reset" signal winding 257 are wound about a leg of the minor aperture 259. Connected to "reset" signal winding 257 is a "reset" circuit 260. Connected to one end of input winding 256 is a signal input 261 and connected to the other end of winding 256 is a signal output 262. In the operation of the delay circuit 205, a low potential level signal applied to the "clear" input 263 of winding 251 initially saturates the entire core in one direction. A low potential level "set" signal applied to the "set" input 264 of winding 252 serves to partially reverse the flux about the path of the major aperture 254 and to thereby store in the path about the minor aperture 259 a predetermined amount of flux which controls the delay of the circuit. It should be noted that during the period the delay circuit is inactive, the signal output 262 is of a low operating potential level (-4 v.) and signal input 261 is at a high operating potential level (0 v.). When the signal, applied on the signal input 261 swings to the relatively low potential level, the current applied to the input signal winding 256 reverses magnetic flux previously stored around the small aperture 259 by the "set" signal, and during the reversal only a small current passes through winding 256 to the -50 v. source. When the reversal is completed the sudden drop in impedance creates a sharp increase in current passing to the -50 v. source. Thus, the effect of this operation is that the negative-going leading edge of the signal on input 261 is delayed in appearing as a positive-going leading edge on the output 262 for a time interval which is dependent upon the amount of the magnetic flux reversal in the path around the minor aperture. Thus, it is only

when all the flux about aperture 259 has been reversed that the signal on the output 262 becomes relatively high in potential level. This signal on the output 262 is held at the high potential level by the low potential signal on the input 261. The reset circuit 260 which includes the "reset" winding 257, is effective, after the signal on input 261 is no longer low in potential level, to cause magnetic flux of the same magnitude as the "set" signal to be reset in the path about the minor aperture 259. The time required to reset the stored flux is equal to the delay of the circuit. The reset circuit 260 is also connected to maintain conduction through transistor 266 while "reset" signal 265 is present. In this way, the trailing edge of the signal on the output 262 is delayed for the same time interval as the leading edge was delayed.

In a similar manner, all subsequent signals coupled to the input 261 of the delay circuit are delayed for the time interval determined by the "set" signal until a "clear" signal is applied to the circuit. For a more detailed description of the adjustable delay circuit of the type described, reference is made to a co-pending U.S. application of Richard K. Gerlach et al., Serial No. 828,910, filed July 22, 1959.

As noted previously, the clock setting circuit 60 operates to synchronize the timing of the clock signals C with respect to the timing of a signal, such as signal T_R , produced by detecting the reference mark 46 on the tape. This clock setting circuit operates at the occurrence of a T_R signal to delay each of the successive clock signals C by a delay time interval determined by the phase difference between the negative-going edge of a C or C' signal and the leading edge of a T_R signal.

As shown in FIG. 8a, a clock pulse C, provided by the reading head 37, is shaped as a square wave, i.e., to periodically swing between a relatively high operating potential level and relatively low operating potential level. As shown in FIG. 8, this signal is amplified in amplifier 217 and inverted in inverter 208 to form on separate leads the respective signals C and C' which signals are complements of each other, i.e., when signal C is at the high potential level, signal C' is at the low potential level, and vice versa.

As previously described in connection with FIG. 1, and as illustrated in FIG. 8a, signal T_R , produced by detector 10, operates to trigger flip-flop G1 into a true state. During the time period the flip-flop G1 is in the true state, its output G_1 is at the high potential level and its output G_1' is at the low potential level. Thus, the outputs from the G1 flip-flop rather than the T_R signal, are directed into the clock setting circuit 60 to set into this circuit a desired amount of delay, and thus initiate its operation.

As shown in FIG. 8, the G_1 and C signals are fed through an "or" gate 214 whose output is connected to the "set" input 264 for the first delay circuit 205. As will be more clearly understood infra, this output from the "or" gate 214 also provides the "clear" input signal for a second delay circuit 206. In a similar manner, the G_1 and C' signals are fed through an "or" gate 222 whose output is connected to the "clear" input 263 for the first delay 205 circuit and the "set" input for the second delay circuit 206.

Referring to the first delay circuit 205, when the flip-flop G1 is in its false state, prior to receipt of the T_R signal on its true trigger input g_1 , clock signals C are applied to the "set" input of the first delay circuit 205, and clock signals C' are applied to the "clear" input of this first delay circuit 205. The waveforms for the "clock," "set" and "clear" signals as applied to the first delay circuit 205 are shown in FIG. 8a. For such operation, each low potential level portion of clock signal C, as evidenced at the output of "or" gate 214, sets a delay into the delay circuit 205, and the following low potential level portion of clock signal C', as evidenced at the output of "or" gate 222, clears this delay from the circuit in

preparation for setting by a subsequent "set" signal. The important operation to note here is that prior to flip-flop G1 being in a true state the circuit is cleared each clock signal period. For this condition the output from the delay circuit is of no concern since the false state of the G1 flip-flop prevents any signals on the output 262 of delay circuit 205 from passing through the "and" gate 220.

Now then, if during the operation of the character reader of FIG. 1, the T_R signal is produced, the flip-flop G1 is triggered true, as previously described. As shown in FIG. 8a, if output G1 swings to the high operating potential level at the instant the clock signal C is at its low potential level, the "set" signal 218, fed into the first delay circuit 205 is shortened, as shown, depending on the occurrence of the positive-going edge 212 of the G1 signal within the period that the C signal is at its low potential level. As a consequence of the shortened "set" signal 218, the period of delay set into the delay circuit is likewise shortened.

The "clear" signal input to the delay circuit 205 is now cut-off since output G1 is high in potential level and maintains the output of the "or" gate 222 at the high potential level. It should be noted that the portion of the input signal waveform C, designated 210 in FIG. 8a, is applied onto the input 261 of the delay circuit 205 simultaneously with the application of the "set" signal 218. The "set" signal serves to hold the signal output 262 at the low potential level, such that the formation of the first output signal 211 follows the "set" signal 218, in time, as shown in FIG. 8a. The first delay circuit 205 now resides in a condition in which it is set to provide a fixed interval of delay for all subsequent clock signals C, provided at its signal input 261.

Since signal C' was at its high potential level, at the time flip-flop G1 was triggered true, a flip-flop Q1 is left in the false state having a high level signal on output Q1', as shown by the waveform Q1' in FIG. 8a. This condition assures that the output of delay circuit 205 passes through gate 220 to provide signals C_s . This operation prevails for a number of clock periods until flip-flop G1 is triggered false in accordance with the condition on the false trigger input q_{G1} shown in FIG. 1.

It should be obvious that the positive-going leading edge 212 of the signal G1, as shown in FIG. 8a, may occur during either the relatively low or relatively high potential level portion of the cycle of the clock signal C, and it is desired to set the clock setting circuit during either portion of its cycle. Thus, to provide a properly initiated delayed series of clock signals during the high potential level portion of the clock signal C, the second adjustable delay circuit 206 is provided in which clock signal C' coupled to its signal input are the complements of the clock signal C. It should be noted, that clock signal C' is at the low level potential when clock signal C is at the high level potential, and vice versa. As previously discussed, the "set" signal for the second delay circuit 206 is derived from the "or" gate 222, and the "clear" signal for the circuit 206 is derived from the "or" gate 214. If the T_R signal triggers the G1 flip-flop into a true state during a period that clock signal C' is low in potential level, then a "set" signal passes through the "or" gate 222 to set a delay into second delay circuit 206 such that this delay circuit can now, in response to clock signals C', provide the properly delayed C_s clock signals.

The adjustable delay circuits are designed to respond to low potential level input signals. Thus, during any particular initiation of the clock setting circuit 60, only one of the adjustable delay circuits 205 or 206 is active to provide the desired delayed clock signals C_s . The delay circuit activated is the delay circuit receiving the low potential level clock signal C or C' at the instant the flip-flop G1 is triggered into its true state. Thus, at the instant signal G1 is switched to a high potential level, a low potential level "set" signal, whose duration is proportional to the desired delay, is produced either on the output of the

"or" gate 214 by the combination of the G1 signal with the clock signal C, or on the output of the "or" gate 222 by the combination of the G1 signal with clock singal C'.

Flip-flop Q1 has been provided to gate out the output of only the active adjustable delay circuit. During the period that no clock signal output C_s is provided by the setting circuits, i.e., during signal output period of G1', the false state Q1' of flip-flop Q1 follows the clock signals C', as shown by the respective waveforms in FIG. 8a. To trigger the flop-flop Q1, "and" gates 226 and 227 individual to the trigger inputs q_1 and q_{G1} pass clock signals C and C' respectively, to trigger the flip-flop Q1. Upon the occurrence of a singal T_R , for example, which triggers the flip-flop G1 to its true state, the gates 226 and 227 no longer pass clock pulses C and C' and the flip-flop Q1 remains in the last state.

The signal output of the adjustable delay circuits 205 and 206 is passed through the "and" gate 220 or the "and" gate 224, and then through an "or" gate 225 to the output of the clock setting circuit. During the periods that adjustable delay circuit 205 is operative to produce the desired delay, the signal outputs Q1' and G1 open gate 220 to pass the signal output of the adjustable delay circuit 205 through the "or" gate 225. During the periods that the adjustable delay circuit 206 is operative to produce the desired delay, the signal outputs Q1 and G1 open the gate 224 to pass the signal output of adjustable delay circuit 206 through "or" gate 225. Thus, the output from one of the delay circuits, as selected by the Q1 flip-flop, provides the series of clock signals C_s which have been phased with the reference signal T_R . Reference is made to a co-pending U.S. application of Richard K. Gerlach et al., Serial No. 69,050, filed November 14, 1960, which discloses and claims the clock setting circuit shown in FIGS. 8 and 8a, and described supra.

Reference will next be made to FIG. 11 which shows details of the logical circuits which control the operation of flip-flops E1 to E4, inclusive, forming the character scan counter 100, and the associated flip-flops A1 and F1, to enable these components to operate as described in connection with FIG. 1. As shown in FIG. 11, the physical embodiment or mechanization of the logical circuits of the preferred embodiment of the present invention is accomplished by cores and windings. The cores are wound so as to operate in accordance with the inhibit core logic principle, as disclosed in a co-pending U.S. application of Kenneth O. King et al., Serial No. 817,851, filed June 3, 1959.

The respective trigger logic cores of the scan counter 50 flip-flops and associated flip-flops are shown in FIG. 11 as vertically disposed slim rectangles, bearing reference numbers as indicative at the upper end thereof. Windings on a core are indicated by slant lines at intersections of the core with respective selected current signal lines 55 which are shown as horizontal lines. For example, core 244 has a winding for clock signal C_s (double slant line at the intersection of the clock signal line and the core), a winding for bias signal Q, individual windings for each of current signals E2', E3', E4' and P17', and a sense winding connected in sense line e_1 on which is generated the true trigger signal for the E1 flip-flop. The other cores have windings as indicated. The directions of the various current signals are indicated by arrow points in the respective lines at the left of core 230. The convention or symbolism employed in FIG. 11 is well known in the art as the "mirror" notation, wherein if the slant line representing a winding were a mirror and the current in the current lines were a beam of light traveling in the same direction as the current, the light would be reflected either upwardly ("1") or downwardly ("0") according to the direction of the slant line; and the interpretation is that if the light were thus reflected upwardly the current would tend to coerce the core in the direction of the "1" state and if it were reflected downwardly the current would tend to coerce the core to "0." On current-carry-

ing windings, double slant lines indicate a double strength coercive effort, **2I**, and single slant lines denote a single strength coercive effort **1I**. Thus, the clock signal C_s is applied with a **2I** positive coercive (upward) effect and the bias (Q) continually exerts a negative coercive effort of value $-I$ tending to drive or hold the cores to "0." Current signals, such as A_1' , E_1 , E_1' , etc., are termed inhibit signals. They are each of coercive strength **1I** and are individually applied in the negative direction to cores, as indicated. In the absence of any inhibit signals on a core, the double strength coercive effort of the clock signal C_s is able to drive the core to "1," against the bias Q.

In accordance with the inhibit core logic principle, each logical "and" function of a Boolean equation is assigned to be mechanized by an individual core. Thus, in FIG. 11, the logical "and" function $E_2 E_3 E_4 P_{17}$ of equation e_1 is mechanized by core **244**. In applying inhibiting currents to a core in order to mechanize a logical "and" function using the principles of inhibit core logic, the inverses of the signal outputs indicated in the equation are actually applied as inhibiting currents. Thus, it is noted, in FIG. 11, that core **244** has windings for application thereto of inhibit current signal outputs E_2' , E_3' , E_4' and P_{17}' (the inverses of the signal outputs shown by the e_1 equation). FIG. 11a shows a graph of the waveforms of the signals applied to core **244**. The inhibit signals are all shown to be absent during the P_{17} period and consequently core **244** is not inhibited and will be turned over once by the clock signal C_s and again by the bias Q at the termination of the clock signal. Thus, at the termination of the clock signal, a negative-going signal is generated on sense line e_1 which will trigger flip-flop **E1** to a true state.

One of the operations of the scan counter provided by the cores in FIG. 11, is the ability to "clear," i.e., initially reset to zero each of the flip-flops **E1** to **E4**. To accomplish this a "clear" inhibit signal is normally continuously applied and is effective on a core **246**. Sense lines, connected to the false trigger inputs for each of the flip-flops, are linked by windings to this core **246**. Thus, whenever the "clear" switch is opened, as may be done in preparation for initial operation of the circuits, the "clear" inhibit signal is absent and core **246** is permitted to be turned over by the next C_s signal, causing signals to be induced on all the sense lines to trigger all the flip-flops into a false state.

As previously discussed in connection with FIG. 1, the character scan counter **100** is able to advance through count positions S_0 to S_{12} , inclusive. As indicated by the table in FIG. 10, each of these count positions is defined by a unique combination of true or false states of the four flip-flops **E1**, **E2**, **E3** and **E4** included in the scan counter. Thus, count S_0 is defined by each of these flip-flops **E1** to **E4**, inclusive, being in a false state (storing a binary digit "0"); count S_1 is defined by flip-flop **E4** being in a true state (storing a binary digit "1"), and flip-flops **E1**, **E2** and **E3**, each being in a false state; and each of the remaining counts S_2 to S_{12} are defined as storing binary digits as shown in the table of FIG. 10. The trigger inputs for each of the flip-flops **E1** to **E4**, inclusive, are mechanized to change these flip-flops from the states representing the existing count of the scan counter to the states representing the next following count of the counter in response to a count signal P_{17} of the subcolumn counter **68**.

The Boolean equations defining how each of the flip-flops **E1**, **E2**, **E3**, and **E4** must be triggered to advance the count of counter **68** are derived by referring to the table in FIG. 10. There it is noted, that the **E1** flip-flop is changed from a false state to a true state on advancing from count S_7 to S_8 . An examination of the unique conditions of count S_7 indicate that the true trigger input e_1 for the **E1** flip-flop can be defined by equation $e_1 = E_2 E_3 E_4 P_{17}$. As previously discussed in connection with FIG. 11, the core **244** is inhibit wound

with outputs E_2' , E_3' , E_4' , and P_{17}' to perform this logic. The sense winding e_1 on core **244** will thus provide an output signal thereon to trigger flip-flop **E1** into a true state, if signals are absent on all the inhibit windings of core **244**. It is noted on moving down the table from count S_0 to S_{12} that the **E1** flip-flop never changes from a true state to a false state, and hence, no false trigger input for the **E1** flip-flop is needed during such advance.

On examining the action of **E2** flip-flop during the counting shown by the table in FIG. 10, this flip-flop is changed to a true state upon advancing from count S_3 to S_4 , and again upon advancing from S_{11} to S_{12} . Thus, the true trigger input e_2 for the **E2** flip-flop can be defined as: $e_2 = E_1 E_2 E_3 E_4 P_{17} + E_2' E_3' E_4 P_{17}$. These two logical "and" functions for equation e_2 are mechanized by applying the inverses of the output current signals, as defined by the equation, onto the windings of cores **240** and **241**. It should be noted here that the common sense line e_2 passing through these cores logically sums the two "and" or product functions. A similar examination of the table indicates the **E2** flip-flop changes from a true state to a false state upon advancing from count S_7 to count S_8 . This can be defined by the equation

$$e_2 = E_2 E_3 E_4 P_{17}$$

which equation is mechanized by the windings on the core **243**.

In a similar manner, the count trigger equations for the **E3** and **E4** flip-flops can be derived. These equations are as follows:

$$\begin{aligned} e_3 &= E_2 E_3' E_4 P_{17} + A_1 E_3' E_4 P_{17} + E_1 E_3' E_4 P_{17}, \\ e_3' &= E_3 E_4 P_{17}, \quad e_4 = E_1 E_4' P_{17} + E_2 E_4' P_{17} + E_1' E_4' P_{17}, \\ e_4' &= E_4 P_{17}. \end{aligned}$$

The three logical "and" functions included in the e_3 equation are mechanized by the windings on cores **236**, **237** and **238**; and the one logical "and" function in the e_3' equation is mechanized by the windings on core **239**. The three logical "and" functions included in the e_4 equation are mechanized by the windings on cores **232**, **233** and **234**; and the one logical "and" function in the e_4' equation is mechanized by the windings on core **235**.

In addition to designing the scan counter **100** to advance from the count it is in, to the next count, as indicated by the table of FIG. 10, the counter is designed to reset to count S_0 , when it is in count S_{12} at the P_Y count of a cycle of the subcolumn counter.

Thus, by examination of the table in FIG. 10, it is noted that in changing from S_{12} to S_0 , only flip-flops **E1** and **E2** need be changed to a false state since flip-flops **E3** and **E4** are already false during count S_{12} . The reset equations are as follows:

$$\begin{aligned} e_1 &= E_1 E_2 P_Y \\ e_2 &= E_1 E_2 E_3' E_4' P_Y \end{aligned}$$

The cores for mechanizing those reset equations are designated by reference numerals **245** and **242** in FIG. 11.

It should be noted that the scan counter operates to advance to S_1 , after being reset to S_0 , only if flip-flop **A1** is in a true state at P_{17} of a scan cycle of a column. Furthermore, the scan counter will advance to S_2 only if the flip-flop **A1** is in a true state at P_{17} of the next scan cycle of this same column. If the **A1** flip-flop is not set true in the next scan cycle for the column, it is an indication that the setting of flip-flop true during the previous scan of the column was due to an erroneous mark on the tape, for example. Thus, instead of advancing to S_2 , the scan counter is designed to reset to S_0 again. This is indicated by the "and" function $A_1 E_3' E_4 P_{17}$ included in the e_3 counting equation. If the **A1** flip-flop is set true during two consecutive scan cycles of a character, after the scan counter has been reset to S_0 , the scan counter will advance at P_{17} of consecutive scans of the

character irrespective of the condition of the A1 flip-flop.

In addition to counting scans, the scan counter, at P₁₈ of a cycle of the subcolumn counter, is provided with the ability to transfer the contents of its flip-flops E1 to E4, inclusive, to a column of cores of the memory 104, as selected by the output of the column counter. Further, the scan counter 100 is arranged to be "set," at P₁ of a cycle, with data stored in a column of cores of the memory 104, as selected by the output of the column counter 80. A portion of the circuits of the scan counter memory 104 is shown in FIG. 7. The memory is provided with eight columns of cores, one corresponding to each of the columns of a tape (FIG. 2). Each column of cores includes five cores, one corresponding to each of the five flip-flops E1, E2, E3, E4, and F1. The false output signals E₁', E₂', E₃', E₄' and F₁' provided by these flip-flops are respectively applied on individual windings provided for each row of cores. A "write" circuit is provided for each of the columns of cores; and a "read" circuit is provided for each of the columns of cores. The "write" circuit for the first column of cores, shown on the left in FIG. 7, comprises a circuit from ground through channel select transistor 270 and through drive line 271, which is wound on each of the first column cores, to a common line 272, and then through timing transistor 273 to a -v. source. The drive line 271 is wound on each of the cores in a column in a direction which is reversed in direction from the direction in which the signal lines E₁', E₂', etc., are wound on the respective cores of the column. Thus, to "write" into the first column of cores, if signal K₁ is present to enable transistor 270 to conduct, and signal P₁₈ is present to enable transistor 273 to conduct, each of the cores in the first column will turn over unless inhibited by a signal on one of the signal lines E₁', E₂', E₃', E₄', F₁'. In a similar manner, when one of the other signals K₂ to K₈ is effective, the information in the E1 to E4 and F1 flip-flops will be written, at P₁₈ time, into a selected column of cores in the memory, by a current drive signal passing from ground to the -v. source.

The "read" circuit for the first column of cores comprises a circuit from ground through the channel select transistor 270 and through drive line 274, which is wound on each of the first column cores, to a common line 276, and then through timing transistor 275 to the -v. source. The drive line 274 is wound through the first column cores in a direction which is reversed to the direction of the windings of drive line 271. Thus, to "read" out of the first column of cores, if signal K₁ is present to enable transistor 270 to conduct, and if signal P₁ is present to enable transistor 275 to conduct, each of the cores in the first column, not already in a "zero" state, will turn over, causing signals to be provided on respective ones of the sense lines m₁, m₂, m₃, m₄ and m₅, provided for each row of cores. In a similar manner when one of the other signals K₂ to K₈ is effective, the information in the selected column of cores will be "read" out onto their respective sense lines. The sense lines m₁, m₂, m₃, m₄ and m₅ are respectively connected to the true trigger input lines e₁, e₂, e₃, e₄ and e₅ shown in FIG. 11, resulting in the respective flip-flops E1 to E4, inclusive, and F1 being "set" in accordance with the data read out of the selected column of the memory.

When writing information into the memory from the flip-flops E1 through E4 and F1, during P₁₈, it is also desired to reset these flip-flops to a zero state. Thus, each of the false trigger input lines ₀e₁, ₀e₂, ₀e₃, ₀e₄ and ₀f₁ has a signal P₁₈ applied thereon, as shown in FIG. 11, resulting in the respective flip-flops being triggered to a false state.

The core 247 is provided to initially set the A1 flip-flop true in response to a first character signal T_C sensed by the optical detector 10 during the scanning process.

In this instance, the T_C signal is employed to drive the core, as shown. The sense line for this core connected to input line a₁, is wound in an opposite direction to the other sense windings, so as to enable the A1 flip-flop to be triggered by the signal produced by turning over the core with the drive T_C, rather than the bias Q. As shown, a signal P₁₇ supplied to input line ₀a₁, provides for triggering flip-flop A1 false.

The F1 flip-flop is set true when the scan counter 100 is in count S₂, as shown and described in connection with FIG. 1. Thus, the true trigger input equation

$$f_1 = E_1'E_2'E_3'E_4'P_{17}$$

is derived by defining count S₂ in the table of FIG. 10. This equation is mechanized by core 230 shown in FIG. 11. The F1 flip-flop is triggered false by conditions defined by equation ₀f₁ = F₁P₁₇. This is mechanized by core 231 in FIG. 11.

The subcolumn counter 68 and column counter 80 shown and described in connection with FIG. 1, have their counting and reset operations similarly defined by a table, such as shown in FIG. 10. Accordingly, the trigger inputs of the flip-flops forming these counters may be mechanized by cores wound in accordance with the inhibit core logic principles, as discussed in detail for scan counter 100.

While the form of the invention shown and described herein is admirably adapted to fulfill the features and objects before enumerated as desirable, it is to be understood that it is not intended to confine the invention to the one form or embodiment disclosed herein, for it is susceptible of embodiment in various other forms without departing from the principle involved or sacrificing any of its advantages, and the invention is therefore claimed in any of its forms or embodiments all coming within the legitimate and valid scope of the claims which follow.

What is claimed is:

1. In a character reading system, means for scanning an area for locating individual characters in order to detect line segments forming predetermined portions of the character to produce respective groups of position modulated signals representing individual characters, each character being stylized to have at least first and second spaced portions, each portion having character segments in predetermined position locations; means for progressively scanning the area including the characters by advancing successive sensory traverses across the area in one direction to locate predetermined portions of the characters; means for sensing a leading line segment of the character by at least one of said traverses to produce signals for locating said individual characters in another direction; means for detecting the line segments forming said predetermined portions of the character by simultaneous sensory traverses of the character to produce groups of position modulated signals representing respective characters in response to the sensing by the sensing means of the presence or absence of a segment in each portion of the character; and means coupled to said last-mentioned means for identifying a character in response to said position modulated signals.

2. Apparatus for optically reading characters recorded in a row of a record medium, which characters have been stylized so that segments of lines used in forming the character are positioned in spaced first and second portions of the character, each portion having character segments in predetermined position locations; an optical scanning means providing a pair of moving apertures for progressively scanning across the row of characters; counting means coupled to said scanning means for counting the number of times the presence of each character in the row is sensed by one of the apertures of said scanning means to determine when said scanning means has progressed to where the pair of apertures are positioned over the first and second portions of the characters; output circuit means responsive to said counting means and cou-

pled to said scanning means for producing position modulated signals in response to the signals generated when the apertures of said scanning means scan the line segments located in the first and second portions of the character; and means coupled to said output circuit means for identifying a character in response to said position modulated signals.

3. Apparatus for reading characters according to claim 2 wherein the size of each moving aperture is large relative to the size of minor visible defects in the record medium, whereby the signal resulting from such defects is such a small percentage of the signal produced when viewing a line segment through the aperture, that the noise introduced into the output signal thereby is negligible.

4. Apparatus for reading characters recorded in a row on a record medium, which characters have been stylized such that line segments forming the character are positioned in spaced first and second portions of the character, each portion having character segments in predetermined position locations; a scanning means providing a pair of spaced scanning elements for progressively scanning the record medium in a direction parallel to the row of characters so as to traverse said segments; sensing means for sensing signals generated by said scanning means; counting means responsive to the output of said sensing means for counting the number of times the presence of each character in the row is sensed by one of the scanning elements of said scanning means to determine when said scanning means has progressed to a position to simultaneously scan the first and second portions of the character; output circuit means connected to the output of said sensing means for producing position modulated signals in response to the signals generated when said scanning means scans the line segments located in the first and second portions of the character; and means coupled to said output circuit means for identifying a character in response to said position modulated signals.

5. A system for reading a row of characters printed on a record medium, which characters have been stylized such that segments of lines used in forming the character are located in a plurality of predetermined paths across the character area, each character being stylized to have at least first and second spaced portions, each portion having character segments in predetermined position locations; a scanning means for progressively scanning the row of characters so as to traverse said segments; a timing means for defining the location of each scan along the row of characters; counting means coupled to said scanning means for counting the number of times the presence of each character in the row is sensed by said scanning means to determine when said scanning means has progressed to a position to scan the predetermined paths of the characters; output circuit means coupled to said timing means and said scanning means for producing position modulated signals corresponding to the relative position of signals generated upon scanning the line segments located in the predetermined paths of each of the characters in a row; and means coupled to said output circuit means for identifying a character in response to said position modulated signals.

6. A system for reading a row of characters recorded on a record medium, which characters have been stylized such that segments of the lines used in forming the character are positioned in at least first and second predetermined portions of the character, each portion having character segments in predetermined position locations; scanning means for progressively scanning the row of characters so as to traverse said segments; timing means for providing outputs identifying the location of each scan as it moves along the row of characters; counting means coupled to said scanning means for counting the number of times the presence of each character in the row is sensed by said scanning means to determine when said scanning means has progressed to a position to scan said predetermined portions of the characters; output

5 circuit means coupled to said scanning means for producing position modulated signals in response to the signals generated when said scanning means scans the line segments located in said predetermined portions of a character; resetting means connected to said timing means and said output circuit means and responsive to the first signal received by said output circuit means to reset said timing means such that the outputs thereof identify the relative position of the signals received by said output circuit means as said scanning means scans the predetermined portions of a character; and means coupled to said output circuit means for identifying a character in response to said position modulated signals.

7. Apparatus for reading one or more characters recorded in a row on a record medium, which characters have been stylized such that segments of lines used in forming the character are positioned in first and second portions of the character, each portion having character segments in predetermined position locations; a scanning means for progressively scanning the record medium in a direction parallel to the row so as to traverse said segments; counting means for counting the number of times the presence of each character in the row is sensed by said scanning means to determine when said scanning means has progressed to a position to scan the first and second portions of the character; translating means for translating the signals generated when said scanning means scans the line segments located in the first and second portions of the character, and for producing position modulated signals in response to the presence or absence of a segment in each portion of said character; and means coupled to said translating means for identifying a character in response to said position modulated signals.

8. A system for reading characters which have been stylized such that segments of the lines forming the character are positioned in at least first and second predetermined portions of the character, each portion having character segments in predetermined position locations; a record medium on which a row of the characters and a row reference mark is printed; scanning means for progressively scanning the row of characters so as to traverse said segments and produce position modulated signals in response to the presence or absence of a segment in each portion of a character; timing means; a resetting circuit responsive to a row reference mark for resetting said timing means to define the location of the scan along the row of characters; counting means connected to said scanning means for counting the number of times the presence of each character in the row is sensed by said scanning means and providing an output when said scanning means has progressed to a position to scan said predetermined portions of the characters; gating means connected to the output of said counting means for gating out said position modulated signals generated by said scanning means as it scans the line segments located in said predetermined portions of a character; said resetting means responsive to the first signal sensed as said scanning means scans the predetermined portions of a character, to again reset said timing means to identify the relative positions of signals gated out of said gating means; and means coupled to said sensing means for identifying a character in response to said position modulated signals.

9. A system for reading a row of characters recorded on a record medium, which characters have been stylized such that segments of lines used in forming the character are positioned in first and second predetermined portions of the character area, each portion having character segments in predetermined position locations; a scanning means for progressively scanning across the row of characters so as to traverse said segments and produce position modulated signals in response to the presence or absence of a segment in each portion of a character; timing means for providing outputs defining the location of the scan along the row of characters; a scan counter

connected for advancing its count each time the presence of a character in a row is sensed by said scanning means; a memory including circuits connected to said timing circuits for resetting the scan counter, prior to the scanning of each character, with the accumulated scan count stored in the memory for the character, and for storing back into memory the scan count in the scan counter after each character has been scanned; and gating means operable when the output of said scan counter indicates that the presence of a character has been sensed a predetermined number of times to gate out said position modulated signals corresponding to the position of the line segments located in the first and second portions of the character; and means coupled to said sensing means for identifying a character in response to said position modulated signals.

10. A character reading system comprising: a record medium having a plurality of alphanumeric characters recorded in rows thereon, each of said characters being stylized to have first and second portions spaced in a first direction substantially perpendicular to said rows, each portion having character segments located in predetermined position locations in a second direction substantially perpendicular to said first direction, the stylizing of each of said plurality of alphanumeric characters being such that the segments in the first and second portions of each character correspond to a pair of binary numbers which pair is different for each character, means for advancing said record medium in substantially said first direction, scanning means for progressively scanning each row of characters in substantially said second direction as the rows are advanced past said scanning means, signal producing means for producing first and second groups of position modulated signals representing a pair of binary numbers in response to the sensing of the presence or absence of a segment in each position of the first and second portions of a character when said character advances to the correct position with respect to said scanning means, and means coupled to said signal producing means for identifying each character in response to the pair of binary numbers represented by the first and second groups of position modulated signals produced by the simultaneous scanning of the first and second portions of a character.

11. In apparatus for optically translating an alphanumeric character from a record medium, said character being stylized to have at least first and second spaced portions, each portion having character segments in predetermined position locations, optical scanning means for scanning said first and second portions of said character in a direction so as to traverse said segments, optical detecting means coupled to said optical scanning means for producing position modulated output signals in response to the sensing by said sensing means of the presence or absence of a segment in each position of said portions, means for differentiating said position modulated signals and forming therefrom discrete pulses, and means for identifying said character in response to said discrete pulses.

12. In apparatus for translating an alphanumeric character from a record medium, said character being stylized to have at least first and second spaced portions, each portion having character segments in predetermined position locations, scanning means for scanning said portions of said character in a direction so as to traverse said segments, means responsive to the vertical alignment of said character to determine the correct positioning of said scanning means with respect to said portions, signal producing means coupled to said scanning means for producing position modulated signals in response to the sensing by said sensing means of the presence or absence of a segment in each portion of said character, and means coupled to said signal producing means for identifying said character in response to said position modulated signals.

13. In apparatus for translating an alphanumeric character from a record medium, said character being stylized to have at least first and second portions spaced in substantially a first direction, each portion having character segments located in predetermined position locations in a second direction substantially perpendicular to said first direction, scanning means for progressively scanning said character in substantially said second direction, means responsive to the alignment of said character in said first direction to determine the correct positioning of said scanning means with respect to the first and second portions of said character, signal producing means coupled to said scanning means for producing position modulated signals corresponding to the sensing by said sensing means of the presence or absence of a segment in each position of said first and second portions, and means coupled to said signal producing means for identifying said character in response to said first and second groups of position modulated signals.

20. 14. In apparatus for translating an alphanumeric character from a record medium, said character being stylized to have at least first and second spaced portions, each portion having character segments in predetermined position locations, scanning means for scanning said first and second portions of said character in a direction so as to traverse said segments, signal producing means coupled to said scanning means for producing position modulated output signals in response to the sensing by said sensing means of the presence or absence of a segment in each position of said first and second portions, means coupled to said signal producing means for identifying said character in response to said first and second groups of position modulated signals, and means responsive to the detecting by said scanning means of at least one segment of said character a predetermined number of times to determine the correct positioning of said scanning means with respect to the first and second portions of said character.

30. 15. In apparatus for translating an alphanumeric character from a record medium, said character being stylized to have at least first and second portions spaced in substantially a first direction, each portion having character segments located in predetermined position locations in a second direction substantially perpendicular to said first direction, scanning means for progressively scanning said character in substantially said second direction, means responsive to the detecting by said scanning means of at least one segment of said character to determine the correct positioning of said scanning means with respect to said first and second portions, signal producing means coupled to said scanning means for producing position modulated signals corresponding to the sensing by said sensing means of the presence or absence of a segment in each position of said first and second portions, and means coupled to said signal producing means for identifying said character in response to said first and second groups of position modulated signals.

40. 16. In apparatus for translating an alphanumeric character from a record medium, said character being stylized to have at least first and second portions spaced in substantially a first direction, each portion having character segments located in predetermined position locations in a second direction substantially perpendicular to said first direction, scanning means for progressively scanning said character in substantially said second direction, counting means coupled to said scanning means for counting the number of times at least one segment of said character is scanned by said scanning means, signal producing means coupled to said scanning means and operable in response to said counting means reaching a predetermined count for producing position modulated signals in response to the sensing by said sensing means of the presence or absence of a segment in each position of said first and second portions of said character, and means coupled to said signal producing means for identifying said character in re-

spose to said first and second groups of position modulated signals.

17. A character reading system comprising: a record medium having a plurality of alphanumeric characters recorded thereon, each of said characters being stylized to have at least first and second portions spaced in substantially a first direction, each portion having character segments located in predetermined position locations in a second direction substantially perpendicular to said first direction, the stylizing of each of said plurality of alphanumeric characters being such that the segments in the first and second portions of each character correspond to a pair of binary numbers which pair is different for each character, optical scanning means including a plurality of moving apertures for progressively scanning at least one of said characters in substantially said second direction, signal producing means coupled to said scanning means for producing first and second groups of position modulated signals representing a pair of binary numbers in response to the sensing by said sensing means of the presence or absence of a segment in each position of said first and second portions of a character, and means coupled to said signal producing means for identifying each character in response to the pair of binary numbers represented by the first and second groups of position modulated signals produced by the simultaneous scanning of the first and second portions of a character.

18. In apparatus for translating alphanumeric characters from a record medium, each of said characters being stylized to have at least first and second portions spaced in substantially a first direction, each portion having character segments located in predetermined position locations in a second direction substantially perpendicular to said first direction, the stylizing of each of said plurality of alphanumeric characters being such that the segments in the first and second portions of each character correspond to a pair of binary numbers, which pair is different for each character, optical scanning means including a plurality of moving apertures for progressively scanning at least one of said characters in substantially said second direction, recognition means coupled to said scanning means and responsive to the detecting of at least one segment of a character by at least one of said apertures to determine the correct positioning of the apertures of said scanning means in said first direction with respect to said first and second portions of a character, signal producing means coupled to said recognition means and said scanning means for producing first and second groups of position modulated signals representing a pair of binary numbers in response to the sensing by said sensing means of the presence or absence of a segment in each position of said first and second portions of a character when the character is in the correct position in said first direction with respect to said scanning means as determined by said recognition means, and means coupled to said signal producing means for identifying each character in response to the pair of binary numbers represented by the first and second groups of position modulated signals produced by said signal producing means when the first and second portions of a character are scanned by said scanning means.

19. A character reading system comprising: a record medium having a plurality of alphanumeric characters

recorded in rows thereon, each of said characters being stylized to have first and second portions spaced in a first direction substantially perpendicular to said rows, each portion having character segments located in predetermined position locations in a second direction substantially perpendicular to said first direction, the stylizing of each of said plurality of alphanumeric characters being such that the segments in the first and second portions of each character correspond to a pair of binary numbers which pair is different for each character, means for advancing said record medium in substantially said first direction, scanning means for progressively scanning each row of characters in substantially said second direction as said rows are advanced past said scanning means, said scanning means including at least two apertures spaced so that the first and second portions of each character are simultaneously scanned, recognition means coupled to said scanning means and responsive to the detecting of the alignment of a character in said first direction to determine the correct positioning of each character in said first direction with respect to said two apertures of said scanning means, means defining the location of said apertures with respect to positions along the row of characters, signal producing means for producing first and second groups of position modulated signals representing a pair of binary numbers in response to the simultaneous sensing by said sensing means of the presence or absence of a segment in each position of the first and second portions of a character when the character has been advanced to the correct position in said first direction by said means for advancing with respect to said scanning means as determined by said recognition means, and means coupled to said signal producing means for identifying each character in response to the pair of binary numbers represented by the first and second groups of position modulated signals produced by the simultaneous scanning of the first and second portions of a character.

20. In apparatus for translating alphanumeric characters recorded in rows on a record medium, each character being stylized to have first and second portions spaced in substantially a first direction, each portion having character segments extending in said first direction and being located in predetermined position locations in a second direction substantially perpendicular to said first direction, the stylizing of each of said plurality of characters being such that the segments in the first and second portions of each character correspond to a pair of binary numbers which pair is different for each character, means for progressively scanning each row of characters to locate the alignment of each character in said first and second directions in response to the location of at least one segment thereof, and means for detecting the segments in each position location of said portions to determine the identity of said character.
